UNITED STATES PATENT OFFICE

CHARLES E. KREBS, OF CHICAGO, ILLINOIS

MOP SWAB

Application filed September 13, 1929. Serial No. 392,358.

This invention relates to mop swabs (for use with water for cleansing purposes as distinguished from oil mops, dry mops, and chemically treated mops for dusting, or dish mops), and its principal object is to prolong the life and increase or enhance the efficiency of articles of this nature.

The ordinary mop swab is constructed of a grouped plurality of separate lengths of fibrous absorbent material made of any desirable number of strands with "cut-ends" or "open-ends." When more than one strand is used, two or more strands are twisted or "laid" together in a twine-like or rope-like structure in a relatively loose manner to produce absorbency, a necessary quality in a mop swab used with water. This grouped plurality of such cut-end or open-end separate lengths are usually fastened approximately midway between their ends to a strip of tape or the like, this construction of swab being used with a separate holder or handle not an integral part thereof. Another form of swab is constructed by fastening in various manners, as an integral part thereof, a grouped plurality of such cut-end or open-end separate lengths to the end portion of a handle or stick.

Obviously the natural tendency of these cut-ends or open-ends is to untwist immediately when put into service and rapidly thereafter on account of their comparatively loose twine-like or rope-like structure, which constant disintegrating process causes fibres and batches of fibres to fall away and the swab as a whole to become uneven and stringy at the cut-ends or open-ends making it unsuitable for desirable service, and to rapidly wear out.

I have effectively overcome these objectionable features by producing a mop swab in which any desirable number of single strands of absorbent material are tied together or otherwise fastened together at their cut-ends or open-ends to form separate lengths, or in which separate lengths of absorbent material of multiple strands are tied or otherwise fastened at their cut-ends or open-ends, thereby preventing untwisting at their cut-ends or open-ends when in use, without, however, pre-

venting untwisting under their normal tendency when in service of that portion of the separate lengths between their cut-ends or open-ends and the point where they are fastened to the handle or stick. I substantially prolong the life of the mop swab by retarding the normal disintegrating process at the cut-ends or open-ends, and make it a more efficient cleaning implement by substantially longer retaining its original structure of evenness at the cut-ends or open ends.

The present invention consists, therefore, in a mop swab formed of a grouped plurality of separate lengths of absorbent material with cut-ends or open-ends in which each separate length may be a single strand or any desirable number of strands twisted or "laid" together in a relatively loose twine-like or rope-like structure to produce absorbency, and when single strand separate lengths are used, any desirable number of strands are tied or otherwise fastened together at their cut-ends or open ends to prevent untwisting. When multiple strand separate lengths are used, they are tied or otherwise fastened at their cut-ends or open ends to prevent untwisting or any desirable number of multiple strands may be tied or otherwise fastened together at their cut-ends or open ends to prevent untwisting. It further consists in a mop swab made of a grouped plurality of separate lengths of absorbent mop material stitched transversely or lengthwise at their cut-ends or open-ends to prevent untwisting.

It further consists in the several novel features hereinafter fully set forth and claimed.

The invention is clearly illustrated in the drawings accompanying this specification in which—

Figure 1 is a perspective view of a mop swab embodying one form of the present invention;

Fig. 2 is a detail enlarged side elevation of a fragment of one of the lengths of material from which the mop swab is formed;

Fig. 3 is a detail cross section taken on the line 3—3 of Fig. 2; and

Fig. 4 is a detail fragmentary side eleva-

100

tion of a slightly modified form of the invention.

Referring to said drawings, a mop swab embodying a simple form of the present invention is seen at A in Fig. 1, and, in accordance with one form of swab, is composed of a plurality of separate lengths *a* of absorbent material, usually formed of twisted together individual strands *a'* of fibrous material having cut-ends or open-ends, said separate lengths of material being unconnected except at the place arranged for attachment to a stick or handle. The material from which the separate lengths *a* are made is commonly known as "mop yarn". The separate lengths are usually cut from mop yarn of indefinite length to form separate definite lengths which comprise the mop swab. The ends of the separate definite lengths, which ends are free, may be termed "cut ends" or "open ends". The separate lengths are grouped together to form a swab-like structure and are usually secured together at one place only with a piece of binding strip *b* of tape or the like. Usually the binding strip is sewed to and around the grouped separate lengths of absorbent material approximately midway between the ends thereof, this being the place of attachment of the mop swab to the mop stick or handle. Any desirable number of strands of fibrous material may be used in each separate length of mop yarn, and it is possible to use more than the ordinary number of strands in each length, due to the fact that the ends are fastened together which prevents untwisting of the end portions of the material, but does permit the untwisting of the remainder of the lengths.

The strands of each separate length of material are fastened together adjacent their cut or open end portions in any suitable manner, as, for instance, by running a row of stitches *a²* along the length of the material for a short distance from the cut ends thereof. The stitches fasten the individual strands together at the cut end portions of the separate lengths of material and effectively prevent said end portions from untwisting under usage without, however, preventing the remainder of the lengths of material from untwisting. As a result, the individual strands themselves are prevented from untwisting, and, consequently, the fibrous material is kept intact, thereby not only prolonging the life of the mop swab and increasing its efficiency, but effectively preventing rapid disintegration of the material from usage, and the depositing of pieces thereof on the floor and in the mop pail.

In the modified form illustrated in Fig. 4, the stitches *a³* are shown as extending transversely of the material. It will be perfectly obvious that means other than stitches

formed of thread may be employed for fastening together the several individual strands of each length of material.

When floors are mopped with a mop swab constructed in accordance with the method above described, it is found that practically no lint or other small particles of the mop material are left upon the floor. Furthermore, very little additional expense is required to fasten together the individual strands of each separate length of material, inasmuch as the stitches may be readily formed in the material by automatic machinery when being run off the twisting mechanism.

By the term "separate lengths" in the specification and claims, is meant that the individual lengths which comprise the mop swab are not connected together in any manner except at the point of attachment with a handle and that their free ends are cut or open.

More or less variation of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

1. A mop swab composed of a plurality of relatively loose twisted separate lengths of absorbent material grouped for attachment to a handle and having cut ends, each separately fastened at the cut end portion by stitches.

2. A mop swab composed of a plurality of relatively loose twisted separate lengths of absorbent material grouped for attachment to a handle, and having cut ends, each separately fastened at the cut end portion by stitches running lengthwise of the material.

3. A mop swab composed of a plurality of relatively loose twisted separate lengths of absorbent material grouped for attachment to a handle and having cut ends, each separately fastened at the cut end portions by stitching running transversely of the material.

CHARLES E. KREBS.
